LOCK

Lyle B. Shinn, Chicago, Ill., assignor to Chicago
Lock Company, Chicago, Ill., a corporation of
Illinois

Application October 28, 1932, Serial No. 639,938

8 Claims. (Cl. 70—104)

The present invention pertains generally to locks. More particularly, the invention relates to that type of lock which is designed for use as a padlock and comprises (1) a main lock-member which has a bore extending therethrough; (2) a plug which is mounted rotatably in the bore and embodies a key slot in the front end thereof; and (3) a plurality of spring-pressed, key-operable, plate tumblers which extend transversely through and are mounted slidably in the plug and cooperate with longitudinal grooves in the main lock-member to hold the plug against rotation when the key for the lock is removed from the plug.

One object of the invention is to provide a lock of this type which comprises a complementary lock-member in addition to the main lock-member, and in which the two lock-members embody oppositely facing jaws and are adapted to be shifted into and out of a locking position wherein the jaws substantially abut, by means of a screw which is connected fixedly to the rear end of the plug, extends through an internally threaded bore in the complementary lock-member and operates when the plug is rotated in one direction by way of the key, to shift the complementary lock-member towards the main lock-member and into its locking position and upon rotation of the plug in the opposite direction to shift the complementary lock-member away from the lock-member and into an unlocked position, and also operates upon removal of the key from the plug and the resultant locking of the plug, to hold the complementary lock-member in a fixed position with respect to the main lock-member.

Another object of the invention is to provide a lock of the last mentioned character in which the complementary lock-member is held against rotation relatively to the main lock-member and is confined to rectilinear movement to and from the main lock-member by means of a pin which is attached to one of the members and fits slidably within a socket in the other member.

A further object of the invention is to provide a lock of the padlock variety which is generally of new and improved construction, may be manufactured at a low and reasonable cost and is exceedingly efficient in proportion to its size.

Other objects of the invention and the various advantages and characteristics of the present lock construction will be apparent from a consideration of the following detailed description.

The invention consists in the several novel features which are hereinafter set forth and are

more particularly defined by claims at the conclusion hereof.

In the drawing which accompanies and forms a part of this specification or disclosure and in which like numerals of reference denote corresponding parts throughout the several views:

Figure 1 is a perspective of a lock embodying the invention;

Figure 2 is a transverse section through the screw which operates in response to rotation of the plug by the key to shift the complementary lock-member into and out of its locking position;

Figure 3 is a longitudinal section illustrating in detail the construction of the two lock-members and the tumbler-equipped plug and exhibiting the manner in which the pin serves to confine the complementary lock-member to rectilinear movement only toward and away from the main lock-member;

Figure 4 is a transverse section on the line 4—4 of Figure 3; and

Figure 5 is a detail longitudinal section showing the manner in which the tumblers upon removal of the key, coat with the grooves in the main lock-member to lock the plug and screw against rotation.

The lock which forms the subject matter of the invention is adapted for use as a padlock and comprises a main lock-member 6, a plug 7 and a complementary lock-member 8.

The main lock-member is elongated. It is formed of any suitable hardened metal and embodies a longitudinally extending bore 9 and a lateral extension 10 at one side of the bore. The bore extends from one end of the main lock-member to the other and serves as a bearing in which the plug 7 is mounted rotatably. The extension 10 is formed integrally with the main lock-member 6 and is cut away or shaped at the rear end thereof so as to form a rearwardly extending, stud-like jaw 11. The outer end of this jaw is substantially flush with the rear end of the main lock-member 6, as clearly shown in Figures 3 and 5 of the drawing.

The plug 7 has a longitudinal slot 12 for a key 13 and is provided at its front end with an enlarged head 14 whereby it is held against rearward displacement relatively to the main lock-member. The head 14 fits within an annular recess 15 which is formed in the front end of the main lock-member 6 and is in the nature of an enlargement of the front end of the bore 9. The plug is held against removal from the main lock-member 6 by means of a split ring 16. The

90

95

100

105

110

latter is disposed in an annular groove 17 in the head 14 of the plug and projects into a contiguous annular groove 18 around the recess 15. When the plug is inserted into the bore in the 5 main lock-member, the split ring 16 is compressed so that it is confined wholly within the annular groove 17. When the plug is positioned so that the ring is opposite to the groove 18, the ring springs outwardly so that it is partly within 10 the groove 18 and partly within the groove 17 and operates to effect a permanent connection whereby the plug is held against removal relatively to the main lock-member. The plug 7 is locked against rotation in the main lock-member by means of a plurality or a set of key-operable plate tumblers 19. The latter are mounted in a U-shaped frame 20 and are slideable transversely with respect to the plug. The frame 20 fits snugly in a transverse socket 21 20 in the central portion of the plug 7 and is similar in design and construction to that exhibited in Letters Patent of the United States No. 1,644,092. A spring 22 is associated with the frame and operates in conjunction with laterally projecting lugs 23 on the tumblers to force the tumblers, some in one direction and some in the opposite direction, and so that the ends project into longitudinal grooves 24 along the bore 9. The grooves 24 are preferably four in number and are arranged in diametrically opposite 30 pairs. The tumblers are adapted to receive the bit of the key 13 and are constructed so that when the key is in its operative position in the key slot 12, the ends of the tumblers are flush with the periphery of the plug. When the key is in its operative position and the ends of the tumblers are flush with the periphery of the plug, the plug is free so that it may be rotated in the bore 9 by the key 13. When the tumbler ends 35 are positioned in alignment with a pair of the grooves 24, the key 13 may be withdrawn from the key slot 12. Upon withdrawal of the key, the spring shifts the tumblers so that the ends thereof project into the two grooves and lock the 40 plug against rotation relatively to the main lock-member.

The complemental lock-member 8 is elongated and, like the main lock-member 6, is formed of any suitable hardened metal. It is located behind 50 and is longitudinally aligned with the main lock-member and embodies a longitudinally extending, internally threaded or tapped bore 25 and a lateral extension 26. The extension is formed integrally with the complemental lock-member 55 and is cut away and shaped at the front end thereof so as to form a stud-like jaw 27. This jaw is flush with the front end of the complemental lock-member and is adapted when the latter is shifted into engagement with the rear 60 end of the main lock-member to abut against the jaw 11 for locking purposes. The complemental lock-member is shifted into and out of its locking position, that is, to and from the main lock-member 6 by means of a screw 28. 65 This screw is formed integrally with and projects rearwardly from the rear end of the plug 7 and fits within the internally threaded or tapped bore 25 in the complemental lock-member 8. When the plug is rotated in one direction, the screw 70 28 operates to shift the complemental lock-member into its locking position wherein the jaw 27 abuts against the jaw 11. When the plug is rotated in the reverse or opposite direction by manipulation of the key 13, the complemental lock-member is shifted away from the main lock-

member into an unlocked or inoperative position. In order to prevent rotation of the complemental lock-member relatively to the main lock-member 6 and to guide the complemental lock-member rectilinearly to and from the main lock-member, a pin 29 is provided. This pin is secured by a drive fit within, and projects rearwardly from, a hole 30 in the rear end of the main lock-member 6, and fits slidably within an open-ended socket 31 in the complemental lock-member 8. 80 A longitudinal hole 32 is bored in the central portion of the screw 29 so as to facilitate milling or machining of the plug and screw and to accommodate the pointed end of the key 13 as shown in Figure 5. 85

The operation of the lock is as follows:

When it is desired to lock an apertured element (not shown in the drawing), the key 13 is inserted through the key slot 12 into its operative position with respect to the tumblers 19 and is turned so as to rotate the screw 28 in a direction wherein it serves to shift the complemental lock-member 8 into its unlocked position. When the complemental lock-member is in its unlocked position, one of the jaws 11 and 27 is inserted into the 100 aperture in the element and then the key 13 is turned so as to rotate the screw 28 in the direction wherein it serves to shift the complemental lock-member into its locking position. In this position, the jaw 27 abuts against the 105 jaw 11, as previously pointed out, and produces a locking effect as far as the element is concerned. Upon shift of the complemental lock-member into its locking position, the key 13 is withdrawn from the key slot 12 with the result 110 that the tumblers are shifted as hereinbefore described so that the ends thereof project into two of the grooves 24 and lock the plug, as well as the screw, against rotation relatively to the main lock-member 6. When it is desired to release the element, the key 13 is inserted into the key slot 12 and manipulated so as to shift the complemental lock-member into its unlocked position. 115

The herein described lock consists of but a 120 small number of parts and may be manufactured at a low and reasonable cost. It is extremely efficient in operation and is difficult to break or pick because of its construction and size.

The invention is not to be understood as restricted to the details set forth, since these may be modified within the scope of the appended claims, without departing from the spirit and scope of the invention.

Having thus described the invention, what I 130 claim as new and desire to secure by Letters Patent, is:

1. In a lock of the character described, the combination of a pair of elongated, complementary members arranged in end to end relation 135 and embodying coacting lock-means and shiftable towards one another into a locking position wherein said means are rendered operative and away from one another into an unlocked position, one of said members having a bore extending longitudinally therethrough, a plug mounted rotatably, and confined against axial displacement, in the bore and provided with key-operable tumblers for locking it against rotation relatively to said one member, and also provided with a 140 slot for the key in the end farthest from the other member, and a screw connected rigidly to and projecting from the other end of the plug and applied to said other member so that it operates in response to rotation of the plug in one direc- 145

tion to shift the members into locking position and in response to rotation of the plug in the opposite direction to shift the members into unlocked position.

5. 2. In a lock of the character described, the combination of a pair of elongated, complementary members arranged in end to end relation and embodying coacting lock-means and shiftable towards one another into a locking position 10 wherein said means are rendered operative and away from one another into an unlocked position, one of said members having a bore extending longitudinally therethrough and the other member having an internally threaded bore extending 15 longitudinally through it and axially aligned with the bore in said one member, a plug mounted rotatably, and confined against axial displacement, in the bore and provided with key-operable tumblers for locking it against rotation relatively to said one member, also provided with a slot for the key at the end farthest from said other member, a screw connected to the other end of the plug for rotation with said plug and fitting in the internally threaded bore in said 25 other member so that it operates in response to rotation of the plug in one direction to shift the members into locking position and in response to rotation of the plug in the opposite direction to shift the members into unlocked position, and 30 coacting, slidably engaging means for preventing relative rotation of the two members and confining them to rectilinear movement when they are shifted into and out of locking position.

3. In a lock of the character described, the combination of a pair of complementary members embodying coacting lock-means and shiftable towards one another into a locking position wherein said means are rendered operative and away from one another into an unlocked position, 35 a plug mounted rotatably in one of the members and provided with key-operable tumblers whereby it may be locked against rotation relatively to said one member, a screw connected to the plug and arranged so that it is applied to the other member and operates in response to rotation of the plug in one direction to shift the members into locking position, and in response to rotation of the plug in the opposite direction to shift the members into unlocked position, and means for preventing relative rotation of the two members and confining them to rectilinear movement when they are shifted into and out of locking position, comprising a pin connected rigidly to one of the members and fitting slidably within a socket in the other member.

4. In a lock of the character described, the combination of a pair of complementary lock-members embodying opposite facing jaws and shiftable towards one another into a locking position wherein said jaws substantially abut and away from one another into an unlocked position, a plug mounted rotatably in one of the members and provided with key-operable tumblers whereby it may be locked against rotation, a screw connected to the plug and arranged so that it is applied to the other member and operates in response to rotation of the plug in one direction to shift the members into locking position and in response to rotation of the plug in the opposite direction to shift the members into unlocked position, and a pin and socket connection between the two lock-members whereby said members are held against relative rotation and are confined to rectilinear movement when they are shifted into and out of locking position.

5. In a lock of the character described, the combination of an elongated main lock-member having a straight bore extending longitudinally therethrough, an elongated, complementary lock-member having a longitudinally extending, internally threaded bore and arranged so that it is longitudinally aligned with the main lock-member and is shiftable rectilinearly to and from the latter, coacting lock-means applied to the two members and adapted to be rendered operative upon shifting of the two lock-members together, a plug mounted rotatably, and confined against axial displacement, in the straight bore of the main lock-member and provided with key-operable tumblers for locking it against rotation relatively to said main lock-member and also provided with a slot for the key at the end thereof farthest from the complementary lock-member, and a screw formed integrally with and projecting from the other end of the plug and fitting within the threaded bore of the complementary member so that it operates in response to rotation of the plug to shift said complementary member to and from the main lock-member.

6. In a lock of the character described, the combination of an elongated main lock-member having a straight bore extending longitudinally therethrough, an elongated complementary lock-member having a longitudinally extending, internally threaded bore, coacting, slidably engaging means for holding the two members in end-to-end relation and so that they are movable rectilinearly to and from one another, coacting lock-means applied to the two members and adapted to be rendered operative upon shifting of the two members together, a plug mounted rotatably, and confined against axial displacement, in the bore of the main lock-member and provided with key-operable tumblers for holding it against rotation and also provided with a slot for the key at the end thereof farthest from the complementary lock-member, and a screw connected to the other end of the plug for rotation with said plug and fitting within the threaded bore of the complementary member so that it operates in response to rotation of the plug to shift said complementary member to and from the main lock-member.

7. In a lock of the character described, the combination of an elongated main lock-member having a bore extending longitudinally therethrough, an elongated complementary lock-member having a longitudinally extending, internally threaded bore, a pin and socket connection between the two members whereby the latter are supported in end-to-end relation and so that they may be shifted to and from one another, coacting lock-means applied to the two members and adapted to be rendered operative in response to shift of the two members, a plug mounted rotatably in the bore of the main lock-member and provided with key-operable tumblers whereby it may be locked against rotation, and a screw connected to the plug and fitting within the threaded bore of the complementary member and operative in response to rotation of the plug to shift said complementary member to and from the main lock-member.

8. In a lock of the character described, the combination of an elongated main lock-member having a bore extending longitudinally through its central portion and a rearwardly extending jaw along one side thereof, an elongated, complementary lock-member positioned directly behind the main lock-member and having a forwardly
